COMBINED AUTOMATIC COFFEE MAKER AND DISPENSER

Peter Muller-Munk, Pittsburgh, Pa., assignor to The Silex
Company, Hartford, Conn., a corporation of Con-
necticut

Application October 16, 1953, Serial No. 27,209

Term of patent 14 years

(Cl. D2—3)

Fig. 1.

Fig. 2.

Fig. 3.

Fig. 4.

To all whom it may concern:

Be it known that I, Peter Muller-Munk, a citizen of the United States, residing at Pittsburgh, in the county of Allegheny and State of Pennsylvania, have invented a new, original, and ornamental Design for a Combined Automatic Coffee Maker and Dispenser, of which the following is a specification, reference being had to the accompanying drawing, forming part thereof.

Fig. 1 is a perspective view of a combined automatic coffee maker and dispenser embodying my new design.

Fig. 2 is a plan view thereof.

Fig. 3 is a front view thereof.

Fig. 4 is a side view thereof.

The side opposite that shown in Fig. 4 is the same as that disclosed in said figure.

I claim:

The ornamental design for a combined automatic coffee maker and dispenser, substantially as shown and described.
